SWITCH CIRCUIT CONTROLLING DEVICE
FOR RAILROADSFrank X. Rees, Chili, N. Y., assignor to General
Railway Signal Company, Rochester, N. Y.

Application February 20, 1946, Serial No. 648,953

3 Claims. (Cl. 171—777)

1

This invention relates to circuit controlling devices for railroads, and it more particularly pertains to railway switch circuit controllers used in governing electrical circuits in accordance with the positions of the switch points.

It is the usual practice, along a stretch of railway track provided with a signalling system, to provide circuit controllers mechanically connected to the switch points of the respective track switches associated with that stretch of track. Each of such circuit controllers generally comprises mechanically operable contacts that can be adjusted to be closed only when the track switch is in its normal position or only when the track switch is in its reverse position. These contacts are subject to the vibration from the track rails because of their mechanical connection to them, and they are also subject to condensation and frost because of being located close to the ground.

A system is disclosed in the prior application of B. A. Lundy, Ser. No. 612,583, dated August 25, 1945, now Patent Number 2,516,400, issued July 25, 1950, in which it is possible to provide a more favorable housing for the contacts at a point remote from the switch points, such contacts being operated by a relay controlled at the track switch by varying the inductive coupling between primary and secondary windings in an electromagnetic structure. The present invention is to be considered as an improvement in the system disclosed in the above mentioned prior application.

An object of the present invention is to increase the sensitivity of the inductive coupling in such an organization by rendering a primary electromagnetic structure movable in accordance with the operation of the switch points between a secondary electromagnetic structure and a magnetic shunt. Relatively small movement of the primary structure away from the secondary structure produces a considerable reduction in voltage induced in the secondary winding, not only because of the increase in airgap between the two structures, but because the airgap is reduced between the primary structure and the magnetic shunt at the same time so that the shunt diverts a greater portion of the magnetic field from the secondary structure.

Another object of the present invention is to reduce to a minimum the leakage current in the secondary winding when the primary electromagnetic structure is operated away from the secondary electromagnetic structure. This is accomplished by applying the magnetic shunt

2

directly to the primary structure at that time to reduce to a minimum the magnetic flux linkage with the secondary electromagnetic structure. By this arrangement the amount of mechanical movement required for the primary structure is considerably less than that which would be required if no shunt were employed.

Another object of the present invention is to provide a circuit controller having a structure comprising a plurality of variable inductive coupling means operated by a common mechanical connection to the switch points, each of such means being adjustable to render maximum secondary voltage with the switch points in either their normal or reverse positions.

Other objects of the present invention reside in adjustment means and characteristic features and purposes which are in part obvious from the accompanying drawings and in part pointed out as the description progresses.

In describing the invention in detail reference will be made to the accompanying drawings in which corresponding parts are indicated by use of similar reference characters, and in which:

25 Fig. 1 illustrates the manner in which a circuit controller provided according to the present invention is connected to the switch points of a track switch;

Fig. 2 is a plan view of the switch circuit controller with the cover removed;

Fig. 3 is a side sectional view of the switch circuit controller taken along the line 3—3 of Fig. 2 with the switch circuit controller cover added;

Fig. 4 is an end sectional view of the switch circuit controller taken along the line 4—4 of Fig. 2;

Fig. 5 is a schematic wiring diagram illustrating the manner in which the circuit controller may be effective in controlling signals or other traffic controlling devices; and

Fig. 6 is an expanded perspective view of parts of the switch circuit controller associated with one inductive coupled circuit controlling means.

With reference to Fig. 1, a single track switch is illustrated as comprising movable switch points 10 and 11 spaced by a tie rod 12 and a front rod 13. The track switch is illustrated as being operated by a hand-throw switch stand HT in the conventional manner. The switch circuit controller SC is connected to the nearest switch point 11 by the detector rod 14, such rod being secured to the switch point 11 by a switch lug 15 in the usual manner. The track switch has been shown in its reverse position with respect to the main track rails 16 for the purpose of convenience in illustrating the struc-

ture of the switch circuit controller. The signals A and B are illustrated as being provided for governing traffic over the track switch in its respective normal or reverse positions.

With reference to Fig. 2 the switch circuit controller is illustrated as having a general organization comprising case 17, and a crank 18 for operating a cam shaft 19, such cam shaft carrying cams 20 and 21 for the operation of the respective armatures 22 and 23. Such armatures have secured thereto primary electromagnetic structures 45 and 56 which are operated by the cams 20 and 21 respectively.

With reference to Figs. 3 and 4, it is illustrated that the armatures 22 and 23 operate between the respective secondary magnetic structures 24 and 26 and magnetic shunts 25 and 27, such magnetic structures being more clearly illustrated in Fig. 4 in which the armature 22 is operated between the secondary structure 24 and the magnetic shunt 25. Similarly, the armature 23 is operated between the secondary electromagnetic structure 26 and the magnetic shunt 27.

Having thus considered the general organization of the switch circuit controller, the structure of the various parts will be more specifically considered.

With reference to Fig. 2, the crank 18 is provided with a swivel joint connector 28 for connection to the detector rod 14, and the crank 18 is rigidly clamped to one end of the cam shaft 19 by the bolt 29. At the opposite end of the cam shaft 19 a collar 30 is provided which is interchangeable with the detector crank 18 for adapting the switch circuit controller for use with a track switch facing in the opposite direction.

The cams 20 and 21 are securely clamped to the cam shaft 19 by the screws 31. With reference to Fig. 3, the cam 20 is illustrated as having a cam operating surface 32 curved on a radius from the center of the cam shaft 19. Recesses 33 and 34 at the ends of the cam operating surface 32 allow the operation of the armature 22 to a position to provide for maximum energization of the secondary winding S of the secondary electromagnetic structure 24, when the cam 20 is operated so that either of such recesses is in alignment with the roller 43 (see Fig. 6). It is provided that the spacing between the recesses 33 and 34 is such that when the cam is adjusted to operate the armature 22 in respective normal or reverse positions, the full operation of the track switch does not provide sufficient travel of the cam 20 to allow the armature 22 to be again operated at the other extreme position. This condition is illustrated in Fig. 3 where the reverse position of the switch circuit controller is shown in which the armature 22 is held in its position in engagement with the magnetic shunt 25 for the portion of the cam extending from the position 32a on the cam surface to the recess 33. When the track switch is operated to its normal position the roller 43 of the armature 22 is operated to enter the recess 33.

The cam 21 is of similar structure to that specifically described above for the cam 20, but such cam 21 is adjusted so that the armature 23 is allowed to be operated to its upper position (with the track switch in its reverse position as shown) to provide for maximum energization of the secondary winding S¹ (see Fig. 4) because of such armature 23 being in alignment with the recess (not shown) at the upper end of the cam 21. The armature 23 is in its operating position as just described only when the track switch is in

its full reverse position, because there is not sufficient travel of the cam 21 during operation of the track switch to its normal position to allow the armature 23 to be operated into the recess 35 at the opposite end of the cam 21.

It is believed to be readily apparent from the structure of the cams 20 and 21 as just described, that each of such cams can be adjusted to use the recess at either end thereof in accordance with the requirements for closing circuits with the track switch in its respective normal or reverse positions.

With reference to Fig. 6 the structure of the armature 22 is more clearly illustrated. Such armature is pivoted by the pin 36 which is also common to the armature 23 (see Fig. 2). With reference to Fig. 2 the pin 36 is journaled by a center bearing 37 and by bearings 38 and 39 secured to the case 17. Spacers 40 and 41 at the ends of the pin 36 are provided for adjustment in the alignment of the armatures 22 and 23 with their cooperating shunt and secondary magnetic structures.

With reference to Fig. 6, the armature 22 is provided with a transverse pin 42 which is used as a bearing for the roller 43. The roller 43 is biased against the cam surface 32 of the cam 20 (see Fig. 3) by a compression spring 47. The pin 42 is secured in the armature 22 by the cotter pins 44. The armature 22 is preferably of non-magnetic material and it has a U-shaped structure for supporting the respective ends of the laminated soft magnetic structure 45, such structure being secured to the armature by the screws 46.

The armatures 22 and 23 are biased against the cams 20 and 21 respectively by compression springs 47 so that the operation of the armatures 22 and 23 will be provided in accordance with the contour of the respective cams 20 and 21. It will be noted that this particular arrangement is on the side of safety in that any failure of the compression spring 47 allows the associated armature 22 or 23 to drop and thus assume its most restrictive controlling position.

With reference to Fig. 4, the magnetic shunts 25 and 27 each are of a U-shaped laminated soft magnetic structure and such shunts are secured by straps 48 and rivets 49 to the transverse strap 50. The strap 50 is provided with adjustment screws 51 and lock nuts 52 for the purpose of adjusting the height of the magnetic shunt members 25 and 27. The shunts 25 and 27 should be adjusted so that the laminations of the armatures 22 and 23 are in direct contact to close the open sides of magnetic shunts 25 and 27 when such armatures are in their downward operated positions. When proper adjustment is accomplished, the shunts 25 and 27 are firmly secured to the terminal board 53 by suitable bolts 54 and spacers 55, preferably of non-magnetic material. The holes in the terminal board 53 for the bolts 54 are large enough to allow for whatever adjustment is required, or they can be elongated if necessary.

The secondary magnetic structures 24 and 26 are inverted U-shaped soft laminated magnetic structures with secondary coil windings S and S¹ respectively provided on such structures for controlling the respective relays NWP and RWP. The members 24 and 26 are secured to the terminal board 53 by bolts 62 and spacers 63 in a similar manner to the manner described in which the magnetic shunts 25 and 27 are secured to such terminal board. It is unnecessary to provide ad-

justment means for the secondary electro-magnetic structures 24 and 26 other than a loose fit for the bolts 62 in the terminal board holes, because such structures are at the top of the terminal board where they can be readily adjusted by merely loosening the mounting bolts 62 and moving the structures 24 and 26 by hand to provide proper alignment with the armatures 22 and 23 respectively.

It will be noted with reference to Fig. 3 that the secondary magnetic structures 24 and 26 are spaced slightly greater distances away from the terminal board 53 than the magnetic shunts 25 and 27 to provide that the lower ends of such structures will be in proper alignment with the laminated members of the cooperating primary electromagnetic structures 45 and 56 when such primary structures are in their operated positions. In other words, the magnetic shunts 25 and 27 and the secondary magnetic structures 24 and 26 have the center lines of their contact surfaces located on a radius about the pivot pin 36 at which point the armatures 22 and 23 are pivoted. It is also provided that the contact surfaces of the secondary electromagnetic structures 24 and 26 which come into contact with the primary magnetic structures of armatures 22 and 23 respectively are cut at an angle to correspond to the angle which the armatures 22 and 23 assume when in their upper operated positions because of their being pivoted around the pin 36.

With reference to Fig. 5, the primary windings P and P¹ are both steadily energized from a suitable source of alternating current, and the secondary windings S and S¹ receive their energy only by induction from the flux linkage of the primary electromagnetic structures 45 and 56 respectively. It is desirable from the standpoint of providing most sensitive control of the relays NWP and RWP which are energized by the induced voltages of the secondary windings S and S¹ respectively, that the primary electromagnetic structures 45 and 56 be operated below the saturation of their laminated structures in order that the magnetic shunts 25 and 27 respectively may be effective upon operation of such primary magnetic structures away from the secondary electromagnetic structures 24 and 26 to divert the magnetic field from those secondary magnetic structures.

The secondary windings S and S¹ are illustrated as being connected to full-wave rectifier units 57 and 58 respectively, and the direct current neutral relays NWP and RWP are energized by the direct current delivered respectively by the rectifiers 57 and 58. It is illustrated, for example, how signal circuits can be selected by the contacts of these relays, one signal being selected by the normal relay NWP and another signal being selected by the reverse relay RWP. It is desirable to provide circuit connections as illustrated by which the circuits check not only through the desired front contact of the relay used for the required circuit control, but also check that the relay for the opposite position of the track switch has been deenergized. Thus it is shown in Fig. 5 that the energy for feeding signal B is provided through a circuit including back contact 59 of relay NWP and front contact 60 of relay RWP connected in series. Similarly, the circuit for feeding energy to signal A includes back contact 60 of relay RWP and front contact 59 of relay NWP connected in series. It will be readily seen that by this arrangement of interlocking of cir-

cuits it is possible to clear only one of the two signals at one time.

With reference to Fig. 6, it will be noted that the armature 22 is arranged to provide a leverage advantage for the movement of the primary magnetic structure 45 as compared to the movement of the roller 43 by the cam 20. This provides a sufficient amount of travel of the primary magnetic structure 45 to provide for the dropping away of the associated relay NWP when the switch point 11 is a distance greater than approximately one-fourth of an inch away from the associated rail 16 of the main track.

It is well known to those familiar with the art that it is the usual practice to include switch detector contacts in the housing of a power switch machine when a track switch is power operated rather than hand-operated, thus rendering the provision of a separate circuit controller unnecessary. It is, therefore, to be understood that the inductive coupling means provided by the present invention can be modified as required to fit the housing of a power switch machine so that it can be operated in such switch machine to provide the general mode of operation herein described. It is to be understood that such inductive coupling means may also be applied in the switch machine or other apparatus where it is desirable to locate contacts remote from vibration or other adverse operating conditions to be encountered in practice.

Having thus described a specific structure of a railway switch circuit controller as one embodiment of the present invention, it is desired to be understood that this form is selected to facilitate in the disclosure of the invention rather than to limit the number of forms which the invention may assume, and it is further to be understood that various adaptations, alterations and modifications may be applied to the specific form shown to meet the requirements of practice, without in any manner departing from the spirit or scope of the present invention except as limited by the appending claims.

What I claim is:

1. A switch circuit controller comprising in combination, a fixed secondary electromagnetic structure separated by a substantial air gap from an oppositely disposed fixed magnetic shunt, a primary electromagnetic structure, an armature having a pivot point at one end and having said primary electromagnetic structure secured at the other end so as to be disposed in said air gap between said fixed secondary electromagnetic structure and said fixed magnetic shunt, a cam on a cam shaft rotatable between respective normal and reverse positions, biasing means for said armature urging said armature against said cam and against the force of gravity, and said biasing means being effective to urge said primary electromagnet away from said magnetic shunt to an extent limited by the contour of said cam, whereby upon failure of said biasing means said armature assumes a position maintaining said primary electromagnetic structure in close coupling with said magnetic shunt, irrespective of the position of said cam.

2. A switch circuit controller comprising in combination, a stationary secondary electromagnetic structure spaced by a substantial air gap from an oppositely disposed magnetic shunt, a primary electromagnetic structure, an armature having a pivot point at one end and having said primary electromagnetic structure secured there-

to at the other end, said armature having a transversely disposed roller at an intermediate point between said pivot point and said primary electromagnetic structure, a cam on a cam shaft rotatable between respective normal and reverse positions, said cam having a recess formed in its contour for permitting actuation of said primary electromagnetic structure from a position adjoining said magnetic shunt to a position adjoining said secondary electromagnetic structure, and biasing means for said armature urging said roller against said cam so that upon rotation of said cam shaft, movement of said armature from a position with its associated primary electromagnetic structure adjoining said shunt to a position adjoining said secondary electromagnetic structure is effected by said roller dropping into said recess in said cam.

3. A switch circuit controller comprising in combination, a stationary secondary electromagnetic structure having a secondary coil winding, a stationary magnetic shunt spaced opposite and away from said secondary electromagnetic structure, a primary electromagnetic structure, an armature having a pivot point at one end and having said primary electromagnetic structure secured thereto at the other end, said armature having a transversely disposed roller at an intermediate point between said pivot point and said primary electromagnetic structure, and means including a crank and actuating cam organization bearing against said roller and rotatable between normal and reverse position for actuating

said electromagnetic structure by reciprocating movement to selectively adjoin said secondary electromagnetic structure or said magnetic shunt in accordance whether said crank is rotated to said normal or said reverse position.

FRANK X. REES.
